POWDER DISPENSING DEVICE

Stuart C. Stimson, Oklahoma City, Okla.

Application May 15, 1931, Serial No. 537,733

21 Claims. (Cl. 132—78.5)

This invention relates to devices involving permeation of powder or other solid particles, in operations such as dispensing, regulating, distributing, bolting, or gauging; or combinations of such operations.

A purpose of this invention is, first, to provide a novel reservoir powder puff having heretofore unobtainable advantages, such as hereinafter suggested, and, second, to extend one or more of these other new advantages to the greatest possible variety of other permeation operations.

Other objects will be in part obvious from the annexed drawing and in part indicated from the following analysis of this invention, in which reference is made to the accompanying drawing illustrating an embodiment of my idea.

Broadly, my invention comprehends a distensible mechanism of positive action, appropriately embodied and adapted to useful operations involving permeation of particles of solid matter, and characterized by interstices capable of significantly variable permeability to solid particles, whose variations of permeability are effected by manipulation and are accompanied by proportionate variations in the total area enclosed or defined by the portion of the medium affected by such manipulation.

One of the preferred embodiments of my invention is a reservoir powder puff such as shown in the accompanying drawing. In this particular device, the preferred permeation mechanism or medium is pliable and elastic, and is combined preferably with soft material such as cotton or silk, for applying the dispensed powder in the most pleasant and effective manner.

Although other permeation devices have been known, several very valuable additional advantages over the known devices are present in my improved arrangement. For example, powder puffs, although heretofore devised to hold powder and intended to dispense it, have never contained means whereby distribution could be regulated positively and evenly for any practicable length of time, to say nothing of preventing loss of powder when the puff is not in use. Nor have any powder cans or containers been developed which, in certain operations for which my invention is useful, can dispense the powder with any comparable combination of evenness, speed, convenience, and adjustability of amount. For sifting, bolting, or grading of small particles, my invention also offers new means of especial value, by using only a single, simple, and compact screening medium capable of wide yet exact vari-

ations of permeability which are positively, quickly, and conveniently obtained.

In the accompanying drawing, Fig. 1 is a perspective view of a preferred form of a reservoir powder puff embodiment of my invention, shown with a portion cut away to reveal part of the insert and filling segment.

Fig. 2 is a perspective view of the complete puff, with filling valve shown slightly open.

Fig. 3 is a slightly enlarged sectional view taken through Fig. 2 on line 3—3.

Fig. 4 is a detailed view of the structure of the body of the puff, showing the nature of a preferred form of backing and of facing material attached thereto.

Fig. 5 is a perspective view of the elastic insert, with the filling segment partially attached thereto.

The puff, as shown, is composed chiefly of two sections 1 and 2, each of which may be made up of pile material 5 in combination with backing 8. Backing 8 consists preferably of rubber elements 6 interwoven with fabric elements 7. However, this backing might consist, especially in other embodiments, of any other appropriate materials desired, such as springs and wires or even rods, and having any other pattern, degree of porosity, proportion of elastic and non-elastic elements, manner of connection, or any other desired variation from the particular example herein shown, without departing from my invention, providing the resulting unit be distensible, contain interstices, and, under manipulation, vary in area circumscribed as the porosity of said interstices simultaneously varies. Moreover, and also within the scope of my invention, any desired material other than the pile substance here shown, and attached in any other desired way, or merely loosely associated, may be used.

Continuing with the particular embodiment of my invention here shown, segment 4 preferably composed of elastic or distensibly pliable material, here rubber sheeting, is cemented or otherwise secured to insert 3 along edges 9, as indicated in Fig. 5 by the dotted strip 10 extending along one of said edges 9. Segment 4 is left open at both ends to form, in combination with insert 3, a valve for filling the puff with powder and at all other times to prevent passage thereof. If desired, means such as snap fasteners (not shown) may be used to keep the valve more securely closed when not in use, and segment 4 could be fastened otherwise than as here shown, at its end. Insert 3 is also preferably of thin rubber sheeting, secured as by cementing to the back of

section 2 to prevent dissemination of powder through this face. However, the use of insert 3 is optional. Were it absent, segment 4 could be attached to section 2 along edges 9, and at 5 the outer end to section 1 as is done in the device shown.

As another variation within the scope of the puff form of embodiment of my invention, element 3, instead of being used as an insert, might 10 be used in place of section 2, thereby dispensing with the latter. In such case, element 3 might be joined to face 1 as by cementing the edges around the periphery only, thereby obviating the seam 11 of the device shown in the attached 15 drawing.

In the form shown, segment 4 is preferably first cemented as heretofore explained to insert 3 whereupon the latter, with the segment outside, is cemented or otherwise attached to section 20 2. Then sections 1 and 2, with pile sides together, are sewed nearly around, turned inside out, finished as to sewing and slitted at the valve opening whereby with the outer end of segment 4 attached to seam lap of section 2, there results 25 the finished article shown in Fig. 2. Whatever the form of puff adopted, sections 1 and 2 contain space between them sufficient to hold a supply of powder. It is to be noted especially that backing 8 can be so formed as to have any desired 30 degree of porosity, preferably a negligible amount normally, that is, in the absence of manipulation intended to dispense powder. In the process of distension of this backing by manipulation or stretching, the non-elastic elements 7 also lengthen, yet prevent undue stretching of the unit. This lengthening of the non-elastic elements is made possible by such features as looseness of weave, twisted, knitted, or wavy structure of elements, or by decrease in cross-sectional area of 40 the elastic elements when stretched.

It will be seen that by the arrangement of reservoir and dispensing means associated therewith, as above described, there is obtained the advantage of normal substantial impermeability of the 45 dispensing means, due to the contraction of the elastic elements 7, whereas when the dispensing section is manipulated, the powder may pass through the interstices of the backing 8. Such passage or permeating is of course variable and 50 dependent upon the degree of manipulation imparted and is effected in a positive manner with an even distribution of powder. The powder puff, in accordance with the above is compact, simple and of desirable appearance and positively retains the powder until it is desired to be applied. Its porosity is variable, thus suiting the need or 55 preference of an individual user.

While the preferred embodiment as described is in the nature of a powder puff, it will be understood that my invention comprehends many modifications, alternatives and equivalents, and all such are intended to be covered by and included within the scope and range of the invention. Further, my invention is not limited to the foregoing terms but contemplates a wide variety, not only of different applications or embodiments but also of equivalents for any one application or embodiment, to-wit: every new and useful device 60 or new and useful element or combination of elements thereof, coming within the broadest purview and construction possible to the validity of the claims hereinafter appended.

Without further analysis the foregoing will so 70 fully reveal the gist of this invention that others can by applying current knowledge readily adapt

it for various applications without omitting certain features that, from the standpoint of the prior art, fairly constitute essential characteristics of the generic or specific aspects of this invention and therefore such adaptations should

and are intended to be comprehended within the meaning and range of equivalency of the following claims.

I claim:

1. A powder containing puff comprising a container for the powder formed by container sections, a section consisting of interconnected fabric, elastic, and puff elements, the elastic elements normally maintaining said section substantially impervious to the passage of powder therethrough, and capable, when distended, of forming with the fabric elements a plurality of interstices through which the powder may be dispensed from the container to said puff elements for application. 85

2. In a device of the character described, a pliable, mesh-like medium practicably adapted to permeation by particles of solid matter in significantly variable amounts, and elastic members combined with said medium and suitable to regulate permeation therethrough. 90

3. A powder dispensing and applying device characterized by a permeation medium having a soft exterior and interwoven construction, and containing a plurality of elastic elements, said elastic elements being adapted to automatically maintain said medium substantially impervious to powder normally, while permitting said medium to become permeable in variable degrees under appropriate manipulation, permeation taking place through a plurality of interstitial openings between said elements. 100

4. A powder container and dispensing device embodying a pliable permeation member containing non-elastic and elastic materials, said elastic material normally maintaining said member substantially impervious to the passage of powder therethrough, and capable when distended of forming with the non-elastic material, interstitial area through which powder may be dispensed from the container through said member, and in combination with said permeation member, soft material for applying dispensed powder. 115

5. A pliable medium permeable to powder and composed of a backing of mesh-like structure 120 consisting of interwoven fabric and elastic elements, and a facing contiguous to said backing, of soft material. 125

6. A powder dispensing medium of controllable 130 permeability consisting of interwoven fabric and elastic elements, with which is combined powder applying material.

7. A powder containing puff of pliable assembly comprising a container for the powder having a wall portion of soft exterior and embodying elements yielding decidedly elastic reaction to manipulation, said wall portion normally resisting passage of powder therethrough and parts of said wall portion being capable of distortion relative to one another, and when so distorted, providing interstitial area for dispensing powder from said container. 135

8. A powder containing puff comprising a covering or envelope for the powder having a portion thereof normally relatively impervious to the passage of powder therethrough and being capable of substantially normal distention and, when so distended, providing interstitial areas for dispensing powder from the container, said por- 140

- tion having an exterior facing of soft material adapted to apply the powder. 80
9. As a new article of manufacture, a reservoir powder puff containing interstitial dispensing area normally substantially enlargeable by manipulation and containing elastic material adapted normally to maintain such area substantially closed in the absence of such manipulation. 85
10. As a new article of manufacture, a powder puff adapted to contain powder and characterized by a dispensing surface having openings decidedly variable in area under normal manipulation, and containing elastic means adapted to limit effectively the size of such openings in the absence of manipulation. 90
11. A powder container and dispensing device comprising container sections, a section consisting of interconnected fabric and elastic elements, the elastic elements normally maintaining said section substantially impervious to the passage of powder therethrough, and capable when distended of forming with the fabric elements a plurality of interstices through which the powder may be dispensed from the container through said section. 95
12. A powder container and dispensing device embodying a pliable permeation member containing non-elastic and elastic materials, said elastic material normally maintaining said member substantially impervious to the passage of powder therethrough, and capable when distended of forming with the non-elastic material, interstitial area through which powder may be dispensed from the container through said member. 100
13. A powder container and dispensing device comprising a container section embodying fabric and elastic elements and characterized by an interconnected structure yielding interstitial area, said elastic elements normally substantially limiting such interstitial area to a predetermined minimum degree of permeability subject to substantial increase of such permeability upon distention of such elastic elements. 110
14. A device having a hollow interior and an exterior embodying a permeation member having a porous structure and containing means adapted to limit elastically the extent of porosity of said member in the absence of manipulation, said elastic means being adapted to permit substantially different simultaneous changes in the porosity of various portions of said member. 120
15. A powder container and dispensing device embodying a pliable and elastic wall portion normally substantially occlusive and capable of providing, when distended, interstitial area for dispensing powder from the container. 125
16. A powder containing and dispensing device comprising a hollow container for the powder having a dispensing wall portion thereof capable of elastic distention, and when so distended, providing dispensing area enlargeable within normal limits in proportion to the degree of such distention. 130
17. In a powder permeation device, a permeable medium external to confined powder and of substantially pliable assembly, said medium yielding under manipulation, interstitial area enlargeable within normal limits in proportion to effort expended, and, in combination with said medium, a plurality of decidedly elastic elements which resist, without preventing, changes from the relaxed extent of said area. 135
18. In a device adaptable to operations involving permeation of pieces of solid matter, a permeable member characterized by mesh-like structure with interstices adjustable to different sizes, and, interconnected in said member, elements for regulating said variations of size with distinct effectiveness. 140
19. In a device adaptable to operations involving permeation of particles of solid matter, a permeation mechanism characterized by a meshy permeation medium containing interstices susceptible of variation in area under manipulation, and, combined in said medium, elastic elements adapted to restore said medium automatically to its normal condition after such manipulation. 145
20. In a mechanism suitable for operations involving permeation of particles of solid matter, a mesh-like permeation medium of a permeability significantly variable by manipulation, and in combination therewith, decidedly elastic means adapted to resist changes in permeability of said medium by such manipulation. 150
21. In a permeation device practicable for only solid particles, a wall member or sheet containing a plurality of elastic elements and characterized by a plurality of openings between said elements, said openings normally being substantially enlargeable by manipulation against the resilient resistance of said elastic elements. 155
